US0D1041739S

(12) United States Design Patent (10) Patent No.: US D1,041,739 S
(45) Date of Patent: * Sep. 10, 2024

(54) LIGHT FIXTURE

(71) Applicant: KOHLER CO., Kohler, WI (US)

(72) Inventors: Erin Leigh Hoover, New York, NY (US); Nicholas Robert Rindt, Grafton, WI (US); Dennis Lee Snyder, Sheboygan, WI (US); Seth M. Stevens, Los Angeles, CA (US); Maxwell Wasscher, Grafton, WI (US); Luke James Worth, Sheboygan, WI (US); Jovello Tijano Gomez, Jr., Sheboygan, WI (US)

(73) Assignee: Kohler Co., Kohler, WI (US)

() Term: 15 Years

(21) Appl. No.: 29/745,641

(22) Filed: Aug. 7, 2020

Related U.S. Application Data

(62) Division of application No. 29/744,911, filed on Jul. 31, 2020, now Pat. No. Des. 961,834.

(51) LOC (14) Cl. 26-05

(57) CLAIM

We claim the ornamental design for a light fixture, as shown and described.

DESCRIPTION

FIG. 1 is a perspective view of a light fixture showing our new design;

FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The broken lines in the drawings show unclaimed portions of the light fixture and form no part of the claimed design.

1 Claim, 7 Drawing Sheets
